UNITED STATES PATENT OFFICE.

JOHN M. WILLIAMS AND VERNON E. SMITH, OF HARLEM, MONTANA.

MAIL-BAG CATCHER.

1,348,071.

Specification of Letters Patent. Patented July 27, 1920.

Application filed August 22, 1919. Serial No. 319,178.

To all whom it may concern:

Be it known that we, JOHN M. WILLIAMS and VERNON E. SMITH, residing at Harlem, in the State of Montana, have invented new 5 and useful Improvements in Mail-Bag Catchers, of which the following is a specification.

This invention relates to mail bag catchers adapted for use upon trains for catching 10 bags of mail suspended at the sides of the track, while the train is in motion, and has for its object the provision of a basket structure pivotally mounted within a mail car and swingable to be disposed exteriorly 15 thereof in position to engage and catch a sack of mail suspended at the side of a track, this basket structure having connected therewith a catch for holding it in bag catching position, and furthermore having connected 20 therewith a spring whereby upon release of the catch the basket will be swung into the car.

An important object is the provision of a device of this character in which the basket 25 member is detachably mounted upon the car so that it may be removed and used upon different cars.

Another object is the provision of a device of this character in which the bag catching basket is provided at its upper and lower 30 ends with knives adapted to sever cords by means of which the mail bag is suspended.

An additional object is the provision of a device of this character which will be comparatively simple and inexpensive in manufacture and installation, highly efficient in use in being quick in action, which will not tear or otherwise damage the mail sacks, which will be durable in service, and a general improvement in the art.

With the above and other objects and advantages in view, the invention consists in the details of construction to be hereinafter more fully described and claimed, and illustrated in the accompanying drawings in which—

Figure 1 is a fragmentary side elevation showing the outside of a mail car and showing our device extended or swung outwardly 50 into operative position.

Fig. 2 is a side elevation showing the inside of the car with the basket swung inwardly,

Fig. 3 is a vertical cross sectional view on 55 the line 3-3 of Fig. 1, showing the front of the basket member,

Fig. 4 is a horizontal sectional view on the line 4-4 of Fig. 1, showing the basket in top plan,

Fig. 5 is a horizontal sectional view on 60 the line 5-5 of Fig. 2, the line of section being taken through the basket member, and

The remaining figures (7 and 8) are detail views of the mounting of the shaft carrying the basket member.

Referring more particularly to the drawings, the letter A designates the side of a mail car. In carrying out our invention we provide a bearing member 10 which is secured upon the underside of the roof of the 70 car on the inside thereof and which includes a downwardly extending tubular portion 11 which may, in practice, be a section of piping. Secured upon the floor of the car in vertical alinement with the bearing member 75 10 is a bearing member 12 including an upstanding tubular portion 13 which has its upper end cut away on one side, as shown at 14. The lower end of the tubular portion 11 is supported by a flange 15 bolted to 80 the side of the car and the upper end of the tubular portion 13 is supported by a similar flange 16 which is provided with a cut out portion 17 registering with the cut out portion 14.

The basket member which catches the mail sacks comprises a substantially rectangular frame 18 which is covered with suitable wire mesh 20. This frame 18 includes vertically disposed front bars 20^a which are 90 spaced apart and which provide the entrance opening to the basket. The frame 18 is so shaped that the forward edge of the bottom is considerably higher at the rear edge thereof whereby to provide a pocket 95 which will retain the mail bag in position after it is caught. At the top of the basket member are provided frame bars 21 which converge rearwardly and upon which are secured knife blades 22 which are inclined 100 with respect to each other and which preferably have serrated edges. At the lower forward edge of the basket member is provided a knife blade 23 which is angularly disposed and which also has preferably a serrated edge. The blades 22 and 23 are so arranged

with respect to each other that the lower blade 23 will be in advance of and cut in advance of the upper blades 22. The purpose of this construction will be hereinafter 110 made apparent. Connected to or formed upon one of the front bars 20^a of the frame

- 18 are laterally extending arms 24 which are secured to a vertical shaft 25 journaled within tubular portions 11 and 13 of the bearing members. This shaft 25 is inserted 5 within the bearing members by inserting its upper end within the tubular portion 11 of the bearing 10 and then engaging its lower end within the tubular portion 13 by moving the lower end laterally through the cut away portions 14 and 17 of the tubular portion 13 and flange 16. In order that the lower end of the shaft 25 may be held within the tubular portion 13, we provide a sleeve 26 revoluble upon the tubular portion 13 and provided with a slot 27 adapted to be moved into registration with the cut away portion 14 but revoluble so that the slot 27 may be moved out of registration with the cut away portion.
- 20 A spring 28 is provided and has one end detachably connected with an eye bolt 29 secured upon the inside of the car and its other end connected with one of the frame bars 20. The tendency of this spring is to swing the basket member into the car. We further provide a catch member 30 pivoted upon the edge of the doorway of the car and engageable with one of the arms 24 for holding the basket member in adjusted position exteriorly of the car.
- 25 In the use of the device, a sack of mail to be caught is suspended from the usual hanger, the only difference being that it is suspended by means of cords at each end of the sack instead of by the ordinary hook. The sack being thus suspended, when it is desired to catch the same, the operator stationed within the mail car swings the basket member so that it will be disposed outside of 30 the car and engages the catch 30 upon the associated arm 24. The basket member will thus be held in position. During the travel of the train, when the basket member reaches the mail sack the knives 22 at the top of the basket member and the knife 23 at the bottom thereof will sever the cords which suspend the sack, the cord holding the bottom of the sack being severed in advance of the cord holding the top of the 35 sack. The sack will then be disposed within the basket member and will be effectually retained therein by virtue of the fact that the forward lower end of the basket is higher than the rear lower edge. The operator then disengages the catch 30 from the associated arm 24, whereupon the spring 28 will swing the basket member into the car, after which the sack of mail is of course removed from the basket member.
- 40 When it is desired to remove the basket member from one car to another, it is merely necessary that the operator grasp the sleeve 26 and rotate it until the slot 27 therein registers with the cut away portions 14 and 17, whereupon the lower end of the shaft 25

may be disengaged from the lower tubular bearing portion 13 by lateral movement, subsequent to which the shaft is disengaged from the upper tubular portion 11 by moving the shaft downwardly.

70 While we have shown and described the preferred embodiment of our invention, it is of course to be understood that we reserve the right to make such changes in the form, construction, and arrangement of 75 parts as will not depart from the spirit of the invention or the scope of the subjoined claims.

Having thus described our invention, we claim:—

80 1. A mail bag catcher comprising a bearing member secured at the upper portion of a car upon the interior thereof, a second bearing member disposed at the lower portion of the car vertically beneath said first named bearing member and including an upstanding tubular portion provided with a cut out portion, a basket structure, a shaft carrying said basket structure and disposable within said bearing members and adapted for rotation whereby to dispose said basket interiorly or exteriorly of the car, and a sleeve journaled upon said tubular portion and provided with a slot adapted to register with the cut away portion in said 85 tubular portion whereby to permit insertion or removal of the lower end of said shaft.

90 2. A device of the character described comprising bearing members secured upon the interior of a mail car in spaced vertical relation, a shaft detachably journaled within said bearing members, a basket structure secured to said shaft and including a rectangular frame covered with wire screen, 105 said basket structure being swingable to be disposed either exteriorly or interiorly of the car, a spring connected with the car and the frame of the basket member whereby to hold the same normally interiorly of the 110 car, and a catch pivoted upon the car and engaging one element of said frame for holding the basket structure exteriorly of the car.

115 3. A device of the character described comprising bearing members secured upon the inside of a mail car in vertical spaced relation, a shaft journaled within said bearing members, a basket structure including arms secured to said shaft, a substantially 120 rectangular frame-work secured to said arms and covered with wire mesh, and knife blades at the top and bottom of said basket member adapted to sever cords between which a mail bag is suspended.

125 4. A device of the character described comprising a vertically disposed shaft journaled interiorly of a car, a basket structure comprising a substantially rectangular frame including spaced front bars forming 130

the entrance opening to the basket structure, arms extending from one of said bars and secured to said shaft, rearwardly converging bars at the top of said basket structure, knife blades secured to said last named bars, a knife blade secured at the lower forward edge of said basket structure, and wire mesh covering said frame.

5. A device of the character described comprising bearing members secured upon the inside of a mail car in spaced vertical relation, a shaft journaled within said bearing members, a basket structure secured

upon said shaft and including a substantially rectangular frame covered with wire mesh, and cutting members at the top and bottom of said basket member adapted to sever cords between which a mail bag is suspended, the wire mesh forming the bottom of the basket structure and extending downwardly beyond the frame whereby to define a pocket.

In testimony whereof we affix our signatures.

J. M. WILLIAMS.
V. E. SMITH.
